UNITED STATES PATENT OFFICE.

IRVING SMITH, OF NEW YORK, N. Y., ASSIGNOR TO THE CRESCENT WATCH CASE COMPANY, OF NEWARK, NEW JERSEY.

DESIGN FOR A WATCHCASE-BACK.

SPECIFICATION forming part of Design No. 26,922, dated April 20, 1897.

Application filed May 5, 1896. Serial No. 590,380. Term of patent 3½ years.

To all whom it may concern:

Be it known that I, IRVING SMITH, of New York city, in the county of New York, and in the State of New York, have invented a certain new and useful Design for Watchcase Backs or Covers, &c.; and I do hereby declare that the following is a full, clear, and exact description thereof, reference being had to the accompanying drawings, in which—

Figure 1 is a perspective view of a watchcase-back embodying my design, and Fig. 2 is a section through the same.

Letters of like name and kind refer to like parts in each of the figures.

The object of my invention is to provide an effective design for the backs or covers of watchcases, lockets, &c.; and to this end said invention consists in the design for a watchcase-back or similar article, substantially as herein set forth.

The leading feature of my design is a curved concavity or depression at the edge of the back or cover, running entirely around the same and extending from the rim of the back or cover up over the latter to a circular shoulder. As shown in the drawings, where it is

designated by the letter A, the extent of said concavity in a radial direction is from the edge of the back or cover to about one-fifth of the distance to the center thereof, and a slight shoulder a marks its limit, or the innermost point to which it extends.

The surface of the concave portion A may be ornamented by suitable engraving or left plain, according to individual tastes, without departure from the scope of my invention.

The central portion of the back or cover, or that portion within the concavity A, is shown as having a convex unornamented outer surface.

Having thus described my invention, what I claim is—

The design for a watchcase back or cover, or similar article, substantially as set forth.

In testimony that I claim the foregoing I have hereunto set my hand this 17th day of April, 1896.

IRVING SMITH.
